UNITED STATES PATENT OFFICE

PARK KITCHELL, OF WHIPPANY, NEW JERSEY.

IMPROVEMENT IN MACHINES FOR APPLYING POWDER FOR THE DESTRUCTION OF INSECTS.

Specification forming part of Letters Patent No. **187,717**, dated February 27, 1877; application filed June 29, 1876.

To all whom it may concern:

Be it known that I, PARK KITCHELL, of Whippany, in the county of Morris and State of New Jersey, have invented a new and useful Machine for Applying Paris Green or any other Dust or Powder to Plants for the Destruction of Insects; and I do hereby declare that the following is a full, clear, and exact description of the construction and operation of the same, reference being had to the annexed drawings, making a part of this specification, in which—

Figure 1 is a perspective view; Fig. 2, a longitudinal elevation; Fig. 3, a transverse section.

Letter A, Fig. 3, is a perforated cylinder; B, support; C, door to cylinder; D, regulator in cylinder; F, support for pulley G; H, crank; I, band; K, handle.

Operation: The preparation to be used is placed in the perforated cylinder A through the sliding door C. The end of the support B is placed under either arm and held in position by one hand holding the handle K. The crank H turned by the other hand sets in motion the cylinder, and the powder is deposited as desired.

What I claim as my improvement is—
The perforated cylinder A, support B, pulley G, and band I, in combination with the crank H and handle K, arranged as and for the purpose set forth.

PARK KITCHELL.
